UNITED STATES PATENT OFFICE.

WILLIAM H. GLEESON, OF SAN FRANCISCO, CALIFORNIA.

COPYHOLDER.

Application filed September 10, 1924. Serial No. 736,882.

This invention relates to copy-holders, and particularly to a copy-holder adapted to be mounted on a typewriter support rearwardly of the typewriter thereon, and having an upwardly and forwardly extending copy-holding portion adapted in its forward position to support a copy over the typewriter roll, and in its rearward position to be entirely free from any interference with the typewriter. The object of my invention is to provide an improved copy-holder of this type which will in one position hold a copy directly in front of the operator, and in another position will be removed from and entirely free from interference with the typewriter.

In the accompanying drawing I have illustrated one specific embodiment of my invention, but it will be understood that the invention can be modified within the scope of the appended claims without departing from the spirit thereof.

Referring to the figures of the drawing, Fig. 1 is a side elevation of my improved copy-holder.

Fig. 2 is a front view thereof.

Fig. 3 is an enlarged end view of the copy-holding roll, taken on line 3—3 of Fig. 2.

Fig. 4 is a cross-sectional view thereof, taken on line 4—4 of Fig. 2.

Referring more specifically to the drawing by reference characters, 1 indicates a support on which is mounted a typewriter 2 with which my improved copy-holder is adapted to cooperate. This copy-holder comprises broadly three main elements, namely, a base 3, an upwardly and forwardly extending arm 4, and a copy-holding roll 5 at the free end of the arm. The arm is pivotally supported in a pair of uprights 6 at each end of the base 3, the pivot-receiving slots of the uprights being open whereby the arm can be freely lifted therefrom when desired. The arm is adapted to pivot to two positions, as indicated in Fig. 1. The arm is so balanced that gravity pulls the same rearwardly when in the dotted line position (Fig. 1) and forwardly when in the full line position, a pair of lugs 7 being adapted to hold the arm in either of these positions.

The copy-holder proper includes a main roll 5 mounted on the free end of the arm 4. This roll is rotatably mounted on a shaft 8 having its ends extending through slots 9 in the end walls 10 of the holder. The ends of the shaft are supported in elements 11

pivoted to the end walls 10 at 12. The roll can be rotated by knobs 13 on the ends of the shaft. A pair of rolls 14, rotatably mounted on a rod 15 supported in the end walls 10 and by the center bearing shown in Fig. 1, extend through slots in a guard 16 and contact with the roll 5. Springs 17 normally hold the roll 5 in contact with the rolls 14.

The walls 10 are each provided with a cam portion 18 over which extends a bar 19 having the ends thereof bent downwardly at right angles and connected to the ends of the shaft 8. Should it be desired to insert a particularly heavy copy in the holder, the roll 5 can be drawn away from the rolls 14 by moving the bar 19 up the cams 18. A spring-pressed roll 20 is provided on the bar for contacting with the copy on the roll 5.

The construction and use of my improved copy-holder is believed to be obvious. The supporting base 3 is positioned to the rear of the typewriter and entirely out of the way of the operator. In the forward position of the arm 4, the copy-holding roll 5 is positioned over the typewriter roll directly in front of the operator, and in its rearward position the holder is removed from and entirely free from any interference with the typewriter. The arm is preferably made of rather heavy material which, in conjunction with its loose connection with the base 1, provides a steady copy-holding support free from vibration. The arm can be freely lifted from the base when it is desired to close the desk to house the typewriter.

Having thus described my invention, what I claim and desire to secure by Letters Patent is—

1. A copy-holder comprising the combination of a base adapted to be mounted on a typewriter support rearwardly of the typewriter thereon, an upwardly and forwardly extending relatively heavy arm pivotally mounted on the base, a copy-holding roll mounted on the forwardly extending portion of the arm, means for rotating the roll to move a copy held thereby, the arm extending about the rear and top of the typewriter in the forward position thereof and being positioned rearwardly away therefrom in the rearward position thereof, and a stop for limiting the forward movement of the arm, the arm being held in the forward position against the stop by its own weight.

2. A copy holder comprising the combina-

tion of a base adapted to be mounted on a typewriter support rearwardly of the typewriter thereon, an upwardly and forwardly extending relatively heavy arm mounted on the base for pivotal movement on a horizontal axis to forward and rearward positions, copy holding means at the free end of the arm, the copy holding means being positioned above the typewriter in the forward position of the arm and rearwardly thereof in the rearward position of the arm, and a pair of stops respectively limiting the forward and rearward movements of the arm, the arm being held in both these positions against the respective stops by the weight of the arm.

3. A copy holder comprising the combination of a base adapted to be mounted on a typewriter support rearwardly of the typewriter thereon and including a pair of spaced uprights having open pivot receiving slots therein, an upwardly and forwardly extending relatively heavy arm having a pair of supporting pivots adapted to rest in the slots, the arms being movable on the pivots to forward and rearward positions, copy holding means at the free end of the arm, the copy holding means being positioned above the typewriter roll in one position of the roll and to the rear thereof in the other position of the arm, and stop means for limiting the forward and rearward movement of the arm, the arm and its pivots being freely removable from the said base through the said open slots.

4. A copy holder comprising the combination of a main roll adapted to support a copy thereon, means for rotating the roll to

move the copy, a roll cooperating with the main roll to support the copy therebetween, 40 spring means for holding the main roll against the other roll, cam means, and a yoke pivotally secured to the main roll and passing over the cam means whereby the main roll can be adjusted bodily away from the other roll against the action of the spring means by moving the yoke up the cam means.

5. A copy holder for a typewriter comprising an arm disposed in a substantially vertical position rearwardly of the typewriter, a pivotal mounting for said arm whereby it may swing in a vertical plane forwardly and rearwardly relative to the typewriter, the pivotal point of the arm being closely adjacent to the support upon which the typewriter is mounted, copy holding means at the termination of the upper end of the arm, said arm being curved to extend its upper end forwardly so that the copy holder will be arranged over and just above the typewriter when the arm is in a forward position, stop means for limiting the forward and rearward movement of the arm, said stop means being so disposed relative to the pivotal point of the arm so that the greater portion of the weight of the arm will be disposed forwardly of the pivotal point when the arm is in a forward position and rearwardly of the pivotal point when the arm is in a rearward position whereby the arm will normally remain stationary in either position due to the disposition of its weight relative to the pivotal point.

WILLIAM H. GLEESON.
